UNITED STATES PATENT OFFICE.

EDWARD B. ROBY, OF TROY, NEW YORK, ASSIGNOR TO STANLEY M. STONE, OF COHOES, NEW YORK.

DIE AND HEAD FOR FOLDING MACHINES.

Substitute for application Serial No. 179,852, filed July 11, 1917. This application filed May 26, 1923.
Serial No. 642,724.

This invention relates to heads and dies for use in folding machines.

The invention has for its object to provide a die which is susceptible of adjustment into various lengths; which may be readily contracted in length, to facilitate removal of blanks therefrom after their edges have been turned therearound, and which comprises several parts assembled in such novel manner as to normally maintain a practically rigid device embodying a sectional die comprising plates maintained in perfect alignment and presenting a smooth die-surface during the operation of pressing it on a blank. These and other objects I attain by employing a grooved and slotted head, slidably adjustable parts within said head, a swinging spring-controlled part and a sectional die, all as hereinafter fully described and specifically set forth in the annexed claims.

This application is a substitute for my abandoned application Serial No. 179,852, filed July 11, 1917, for "dies and heads for folding machines."

In the accompanying drawings forming part of this specification, Figure 1 is a plan view of the device. Fig. 2 is a longitudinal sectional view taken on the line 2—2 of Fig. 1. Fig. 3 is a similar view showing the device contracted in length. Fig. 4 is a side view. Fig. 5 is an inverted plan view. Fig. 6 is a cross sectional view taken on the line 6—6 of Fig. 2, and drawn on an enlarged scale. Fig. 7 is a fragmentary sectional view taken on the line 7—7 of Fig. 2, and drawn on an enlarged scale.

In the example of my invention illustrated in the accompanying drawings, A, indicates the die-head which is provided with a deep groove 2, which extends throughout its entire length and snugly engages the die-sections B, C and D. The die-section C, is fixed to the head A, by means of a screw 3, and the sections B and D, are adjustably secured to said head by means of screws 4, which pass through slots 5, in the upper wall of the head A.

The die-section B, comprises the fixed part 6 and rocking part 7, having the grooves 8 and 9, which respectively engage the tongues 10 and 11, of the part 6. The parts 6 and 7, are normally held in parallel horizontal alignment by means of the spiral

spring E, which extends through an opening 12, of the part 7, and is secured at its respective ends to pins 13 and 14. The upper horizontal edge parts, of the part 7, of the die section B, normally contact respectively with parallel horizontal parts of the head A and the part 6; and the part 7, is provided with a shoulder e, to prevent accidental inward movement thereof during the operation of pressing the device downwardly.

Each die section has removably secured to its under surface a plate 15; and these, in conjunction, form the die proper and may be of any desired conformation.

One side face of the head A, is provided with a scale F, and the die-sections B and D, are respectively provided with a pointer 16, for registration with said scale, whereby the required length of die may be indicated.

The die-plates 15, are removably attached to the upright parts of the die-sections B, C and D, by means of screws 17, having conical heads 18, which engage countersunk flanges 19, of the plates 15, whereby said plates are braced and securely attached to the upright parts of the die sections, a perfectly aligned and smooth lower surface being maintained for contact with the blanks to be turned.

It is noteworthy that the upright parts of the die-sections snugly engage the deep groove 2, of the head A, maintaining rigidity whereby when the die is pressed on the blank to be turned the plates 15, are in perfect alignment on a horizontal plane. But when it is desired to contract the length of the die it is simply necessary to move the section B, first downwardly and then inwardly, the interlocking tongues and grooves acting to limit the movement and maintain the parts in engagement, as shown by Fig. 3 of the drawings.

In the drawings I have illustrated but one rocking die-section; but a rocking section may be employed at each end if found desirable.

In the operation and use of the invention the die is pressed downwardly and held upon a blank, as shown by dotted lines 20, Fig. 1 of the drawings. Then the edges of the blank are inturned over the die plates, as shown by dotted lines 21, Fig. 2 of the

drawings. After the blank is removed the section B, automatically assumes its normal position, by means of the spring E, and all parts of the die are again in normal horizontal alignment ready to be pressed upon a new blank, the shoulder e, acting to prevent any accidental movement of the interlocked parts, and the normal horizontal alignment of the rocking part 7, fixed part 6 and head A, providing a practically rigid structure. To remove the turned blank the die is contracted in length by simply moving the rocking section 7, into position shown by Fig. 3 of the drawings.

Having thus described my invention, what I claim as new, and desire to secure by Letters Patent, is:

1. In a head and die for folding machines, a head provided with a grooved lower surface and with slots, an intermediary die section engaging the aforesaid grooved surface and secured thereto, tongued fixed parts for the end die sections and rocking parts for said end sections, said rocking parts provided with means engaging the grooved lower surface of said head to preserve the die parts in horizontal alignment and with slotted recesses receiving and engaging the tongues of the aforesaid tongued fixed parts, said slotted recesses being longer than the said tongues and of varying width to permit said end die sections to rock in a vertical plane.
2. In a head and die for folding machines the combination with a head provided with an aligning groove, of an intermediate fixed die-section, an end slidable die-section, and an end die section comprising a fixed part and a part rockable in vertical plane while interlocked with said fixed part and retained in engagement with said head groove and spring-means for maintaining said

fixed and rocking parts in normal alignment, said head having a scale thereon and said end sections having pointers for registering with said scale. 45

3. The combination, with a grooved and slotted head, of an intermediate fixed die-section, an end slidable die-section, and an end die-section comprising a fixed part and a vertically rocking part interlocked therewith and restrained from movement from horizontal alignment, and spring means for maintaining said fixed and rocking parts in normal horizontal alignment. 50

4. In a head and die for use in folding machines, the combination, with a grooved and slotted head, of a slidably adjustable die-section at one end thereof, a fixed die section intermediately located, and a slidably adjustable die-section comprising a fixed horizontal part and a rocking part movable in vertical plane while interlocked therewith, and spring means for maintaining said parts in normal alignment. 55

5. In a device of the character described, the combination, with a grooved and slotted head, and an intermediate normally fixed die-section; of a longitudinally slidable die-section, and an oppositely located slidably adjustable die-section comprising a normally fixed horizontal part having substantially horizontal tongues, and a rocking part having grooves interlocked with said tongues and engaging said head groove to preserve alignment therewith, and spring means for maintaining said parts in normal alignment; said die-sections each comprising an upright part and a horizontal plate. 70

Signed at the city of Cohoes, in the county of Albany and State of New York this third day of March A. D. 1922. 80

EDWARD B. ROBY.
